(57) **CLAIM**

The ornamental design for a hinge for device, as shown and described.

DESCRIPTION

FIG. 1 is a perspective view of a hinge for device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a first alternative position thereof;

FIG. 9 is a perspective view of a second alternative position thereof;

FIG. 10 is a perspective view of a third alternative position thereof;

FIG. 11 is a perspective view thereof in use; and,

FIG. 12 is a perspective view thereof at reduced scale in use. The broken lines shown are included for the purpose of illustrating an environment of use of the hinge for device, and form no part of the claimed design.
